JOHN FAY LOOMIS AND BYRON EDWARD WING, OF SHELBY, IOWA.

APPARATUS FOR CONVERTING MOTION.

SPECIFICATION forming part of Letters Patent No. 352,878, dated November 16, 1886.

Application filed April 30, 1886. Serial No. 200,744. (No model.)

To all whom it may concern:

Be it known that we, JOHN FAY LOOMIS and BYRON EDWARD WING, of Shelby, in the county of Shelby and State of Iowa, have invented a new and useful Improvement in Apparatus for Converting Motion, of which the following is a specification.

Our invention consists in an improved apparatus for converting reciprocating into rotary motion, as will be hereinafter fully described, and pointed out in the claims.

Referring to the accompanying drawings, Figure 1 is a perspective view of our improved apparatus, showing the same arranged in its operative position. Fig. 2 is a perspective detail view of one of the hollow flanged disks and the pawl-disk which rotates therein. Fig. 3 is a vertical longitudinal sectional view. Fig. 4 is a vertical sectional view; and Fig. 5 is a detail view of the adjustable U-shaped spring, hereinafter described.

The same letters of reference indicate corresponding parts in all the figures.

Referring to the several parts by letter, A represents the frame which supports in their operative positions the various portions of our improved apparatus. In one end of this frame reciprocates between the vertical uprights B the vertical rack-bar C, which we have shown 30 rigidly secured to the lower end of the vertically-reciprocating rod D of a windmill, although it is obvious that the toothed racks E might be secured to the lower end of the rod D itself, if desired, without departing from the spirit of our invention.

Journaled in what we shall denominate the "inner end" of the supporting frame A are two parallel shafts, F F, the inner ends of which extend on each side of the rack-bar C, and on the inner portions of these shafts, but somewhat in advance of the rack-bar, are rigidly secured the disks G G, having each the thick annular flange H at its periphery, against the inner surface of which flange the pawls M bear when in operative position. Against the hollow inner face of these flanged disks G fit the pawl-disks I, which turn loosely on the inner ends of the shafts F, each pawl-disk having secured concentrically upon its outer face 50 a pinion, J, which meshes with the teeth of the rack-bar C, while the inner face of each

disk is formed with the circular concentric enlargement K, having the flaring recesses L, in which the inner nearly-circular reduced ends N of the pawls M fit and move. These pawls 55 are made of metal, preferably iron, and have their outer ends formed with the longitudinal recess O, in which is seated and rigidly secured, by the bolts P, or in any suitable manner, the wooden shoes Q, which we prefer to 60 make of maple, and these maple shoes we prefer to cover with a strip, R, of leather on their outer bearing-edge, although the leather may be dispensed with, if desired, as the maple shoe will work readily without it. The inner 65 reduced end of each pawl is formed nearly circular, to adapt it to fit and turn readily in the inner portion of the flaring recess L, the outer sides of the flaring recess being farther apart than the width of the 70 neck of that end of the pawl, by which arrangement the pawl may turn slightly in the said recess, so as to bring its outer bearing-edge into or out of contact with the inner surface of the annular flange H of its disk G, according to the direction in which its pawl-disk I is being rotated by the rack-bar, the flaring jaws of the recesses in the two pawl-disks on different sides of the rack-bar being inclined in opposite directions—on one disk 80 to the right and on the other to the left—so that on the downstroke of the rack-bar the pawls of one disk will be thrown out into engagement with the flange of its disk, while on the upstroke of the rack-bar the pawls of 85 the other disk (which on the previous movement were folded in out of engagement) will in turn be thrown out by the centrifugal action into contact with the annular flange of its disk G, by which arrangement the disks G G 90 are alternately revolved by friction with the pawls, one disk on the downstroke and the other on the upstroke of the rack-bar, both disks being thus revolved in the same direction. This arrangement of the recesses L and 95 the pawls is clearly illustrated in Fig. 4 of the drawings.

To the outer end of each parallel shaft F is secured a gear-wheel, S, and these two gear-wheels mesh with a flanged pinion, T, secured 100 on the inner portion of a longitudinal shaft, U, which carries at its outer end the large

balance drive-wheel V, around which passes belting to convey the rotary motion to any desired point.

It will be seen that by our improved apparatus a continuous revolution of the drive-shaft is obtained, as the said shaft is rotated both on the up and down stroke of the rack-bar, as previously described. By constructing the pawls with the wooden bearing-shoes the pawls are prevented from wearing smooth and slipping on the inner face of the metal flange of the disks G, which would be liable to occur if a plain metal pawl were employed, and the leather strips R aid still further the friction between the pawls and the said flanged disks.

We construct the pumping-rod W of the windmill in two parts, W' W', the adjacent ends of the said parts being connected together by the adjustable U-shaped spring X, the ends of which are formed with the perforations Y Y, which admit of the spring being adjustably secured to the said ends of the rod so as to regulate its tension as desired. It will be seen that this spring serves to take up part of the motion when the windmill is running too fast, thereby equalizing the speed with which the lower portion of the rod W, and therefore the rack-bar, is reciprocated, thereby causing the machinery of our improved apparatus for converting motion to run more smoothly and protecting it from sudden jars and strains, as will be readily understood.

From the foregoing description, taken in connection with the accompanying drawings, the construction, operation, and advantages of our improved apparatus for converting motion will be readily understood. The adjustable U-shaped tension-spring X can be applied to any mill, as it may be moved in or out to regulate its tension as required. A continuous revolution of the drive-shaft and its band-wheel is secured, the said shaft being rotated on each movement of the pumping-rod of the windmill both up and down, while by constructing our improved pawls with the wooden bearing-shoes the bearing-edges of which may be covered with leather, all danger of the said pawls slipping and becoming inoperative is effectually obviated.

We propose to file a separate application for the U-shaped spring in combination with a pump rod or equivalent.

Having thus described our invention, what we claim, and desire to secure by Letters Patent, is—

1. The combination, with the vertically-reciprocating rack-bar, of the two parallel shafts having on their outer ends the gear-

wheels, and having rigidly secured upon them near their inner ends the hollow flanged disks, the disks turning loosely on the inner ends of the said shafts, having on their outer sides the concentric pinions which mesh with the said rack-bar, and having on their inner sides the circular enlargements formed with the recesses having the flaring mouths arranged as described, the metal pawls having the reduced inner ends fitting and turning in the said recesses, and formed at their outer ends with the longitudinal recesses, the wooden shoes secured in the said recesses, and the drive-shaft having at its inner end the pinion and at its outer end the balance drive-wheel, all constructed and arranged to operate in the manner and for the purpose herein shown and set forth.

2. The combination, with the hollow flanged disks, of the pawl-disks having the inner circular enlargements formed with the recesses having the flaring mouths arranged as described, the metal pawls having the reduced inner ends fitting and turning in the said recesses, and formed at their outer ends with the longitudinal recesses, the wooden shoes secured in the said recesses, and the leather strips secured around the bearing-edges of the said shoes, substantially as and for the purpose shown and described.

3. The combination, with the pumping rod of a windmill, consisting of the upper part and the lower part having at its lower end the rack-bar, of the adjustable U-shaped spring connecting the adjacent ends of the said parts together, the two parallel shafts having on their outer ends the gear-wheel and having rigidly secured upon them near their inner ends the hollow flanged disks, the disks turning loosely on the inner ends of the said shafts, having on their outer sides the concentric pinions which mesh with the said rack-bar, and having on their inner sides the circular enlargements formed with the recesses having the flaring mouths arranged as described, the metal pawls having the reduced inner ends fitting and turning in the said recesses, and formed at their outer ends with the longitudinal recesses, the wooden shoes secured in the said recesses, and the drive-shaft having at its inner end the pinion and at its outer end the balance drive-wheel, all constructed and arranged as and for the purpose shown and described.

JOHN FAY LOOMIS.
BYRON EDWARD WING.
